(57) **CLAIM**

The ornamental design for a combined video camera and video tape recorder, as shown and described.

DESCRIPTION

FIG. 1 is a perspective view of a combined video camera and video tape recorder showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof, wherein the video camera is in a first alternating position;

FIG. 9 is yet another perspective view thereof, wherein the video camera is in a second alternating position;

FIG. 10 is yet another perspective view thereof, wherein the video camera is in a third alternating position; and,

FIG. 11 is yet another perspective view thereof, wherein the video camera is in a fourth alternating position.
